UNITED STATES PATENT OFFICE.

SELDEN IRWIN CLAWSON, OF SALT LAKE CITY, UTAH.

PROCESS OF VOLATILIZING ORES.

1,169,530.

Specification of Letters Patent. Patented Jan. 25, 1916.

Application filed May 24, 1911. Serial No. 629,190.

To all whom it may concern:

Be it known that I, SELDEN I. CLAWSON, a citizen of the United States, residing at Salt Lake City, in the county of Salt Lake, 5 State of Utah, have invented certain new and useful Improvements in Processes of Volatilizing Ores, of which the following is a description, reference being had to the accompanying drawing and to the figures of 10 reference marked thereon.

The invention relates to new and useful improvements in the treatment of ores by the process known as volatilization.

It is common in the art to use air as a 15 carrier by which the volatile compounds are taken to a fume arrester or condenser where they are separated from the carrier and the carrier air passes off to the atmosphere. It will be readily understood that by this 20 method all the volatile compounds which are not caught by the fume arrester, pass off into the air and are lost.

An object of the present invention is to provide a process which will reduce to a 25 minimum this loss in the volatile compounds passing off to the outer air.

The invention consists generally in providing a carrier gas which is used over and over again so that any of the volatile 30 pounds which are not separated by the fume arrester, are brought back again to the chamber where the ore is volatilized, where it unites with more of the volatile compounds and passes on again to the arrester.

35 In the drawings, the figure shows more or less diagrammatically an apparatus for carrying out my improved process.

The apparatus consists of a closed chamber 1, which may be of any desired construction 40 commonly used in the volatilizing of ores. The raw ores are pulverized and placed in said chamber. A pipe 2 leads into the chamber and serves as a means for supplying said chamber with any suitable halogen gas and the necessary conditions are brought about to produce volatilization of the ores in the manner well understood in this art. A pipe 3 leads from the chamber 1 to a fume arrester or condenser 4, which 45 may be of any desired type. As herein shown, said condenser consists of a receptacle partially filled with water which is continually agitated by any suitable mechanical means. The pipe 3 extends into the lower part of the receptacle so that any 50

gases or fumes passing through the pipe 3 will be led into the fume arrester beneath the surface of the water therein. This fume arrester however, differs from any of the well known fume arresters, in that it is completely closed so that the gases passing into the same may be collected and led through a pipe 5 which enters the receptacle of the fume arrester near the upper end thereof. The pipe 5 is connected to a pipe 2, by a 60 mixing chamber 6. The mixing chamber 6 is also connected through a pipe 7 to any suitable means for supplying the halogen gas which is to be used in connection with the volatilization of the ores. 65

In the carrying out of my process, the system or apparatus is provided with a certain amount of carrier gas which may be of any desired character which does not act upon the ores, such for example as nitrogen 70 gas. The halogen gas passing through the pipe 7 is mixed with the carrier gas in the chamber 6, and passing through the pipe 2 is led to the chamber 1, where the ores are volatilized and the carrier gas absorbs the 75 volatile compounds which are taken up thereby and conveyed by the carrier gas through the pipe 3 into the fume arrester or condenser. 80

As the carrier gas passes up through the 85 water of the condenser, a part of the volatile compounds will be caught in the condenser. It is impossible however, to separate all of the volatile compounds from the carrier gas. Whatever compounds remain in the carrier 90 gas, will pass along with the same through the pipe 5 into the mixing chamber where further halogen gas is mixed with the carrier gas and the carrier gas continues its travel through the pipe 2 into the chamber 95 1. It will thus be seen that I have provided a complete cycle for the carrier gas which is used over and over again so that any volatile compounds which are not separated from the carrier gas on the first passing 100 through of the fume arrester or condenser will be brought back again to the volatilization chamber where said uncaught portions will unite with more of the volatile compounds and pass again to the fume arrester 105 or condenser. 110

Instead of using a halogen gas to produce the volatile conditions of the ore, it is obvious that a flux could be used for the same purpose in which case of course, the pipe 7 110

could be omitted and the carrier gas would merely pass continually through the system picking up the volatile compounds, conveying the same to the arrester where they will be to a large degree separated from the carrier gas and the uncaught volatile compounds will be conveyed back again to the volatilization chamber and pass through the same with the carrier gas and other volatile compounds to the fume arrester.

If a halogen gas is used instead of a flux, it will be obvious that any surplus of the halogen gas or gases would pass along with the carrier gas or gases to the condenser or 15 arrester, and thence would be returned with the carrier gases to the presence of the ore. This would avoid all possible loss of the halogen gas with which the crushed ore is being treated. Furthermore, it is obvious 20 that instead of using a nitrogen gas or gases which do not attack the ore, a surplus of halogen gas or gases could be used as a carrier, and therefore, it is to be distinctly understood that I do not limit myself to any 25 particular gas or gases as a carrier, neither do I limit myself to any particular method of volatilizing the ores, the essential features being the substantially closed volatilization chamber with the substantially closed fume 30 arrester or condenser, and the connecting pipes forming the system wherein the carrier gas whatever may be its character passes through the volatilization chamber, thence through the condenser and back 35 again to the volatilization chamber, and so on in a continuous cycle.

It may be stated by way of illustration, that a cubic foot of nitrogen gas when fully saturated, will carry two ounces of volatile 40 compounds. If therefore, two liters of halogen gas and one hundred liters of a carrier gas are passed into the volatilization chamber, and the two liters of halogen gas are chemically taken up by the metal in the 45 ore in the furnace, the one hundred liters of carrier gas absorb the volatile halogen compounds formed by the two liters of halogen gas, and are conveyed through the carrier gas to the fume arrester. Let us suppose that the volatile compounds represented by one liter of halogen gas are caught 50 by the fume arrester, then the carrier gas with the other halogen compounds represented by one liter of halogen gas, will pass 55 on to the mixing chamber at which point one liter of halogen gas is added to the carrier gas and the volatile halogen compounds uncaught by the arrester and pass into the furnace or volatilization chamber. This 60 last named one liter of halogen gas will be chemically taken up by the ore, and the carrier gas which already contains the halogen compounds represented by one liter of halogen gas, absorbs the newly formed volatile 65 compounds and passes to the fume ar-

rester, and thus it will be seen that this carrier gas is reused. If the fume arrester caught all or substantially all of the volatile compounds, an increased amount of halogen gas would be added to the mixing 70 chamber. If all of the halogen gas did not chemically combine with the metals in the furnace, then a decreased amount of halogen gas would be added to the mixing chamber.

75

By the proper regulating of the supply of the halogen gas, it will be obvious that certain conditions may be brought about so that a continuous volatilization action is brought about in the furnace and a carrier 80 gas picks up and conveys the volatile products to the fume arrester, and that this action is continuous. Furthermore, inasmuch as there is no chance for the halogen gas or gases or the carrier gas or gases to escape 85 from the apparatus or system, there will be no loss of the volatile compounds and the process may be continued until the finishing of the treatment of the ore.

85

As above noted the ore could be fluxed to 90 produce the halogen gas necessary for the volatilization of the metals or the ore could be fluxed in place of part of the halogen gas, and the remaining part could be supplied at the mixing chamber. A simple condenser 95 baghouse electrostatic liquid or any kind of an arrester could be used. Furthermore, any kind of a furnace may be used which would not interfere with the reuse of the carrier.

100

In order to circulate the carrier gas and regulate the pressure thereof, mechanical means may be employed. Furthermore, leakage loss of gases may be overcome by attaching a fume arrester in the circuit, exhausting some of the carrier gases, thus causing ingress of air at defective points.

105

Having thus particularly described my invention, what I claim as new and desire to secure by Letters Patent is:—

110

1. A process for the removing of the volatile compounds or metals in a volatilization extraction which consists in associating a carrier gas or gases with ore to absorb and convey the volatile compounds or metals to their proper place and extract part or all of the compounds and return the carrier gases to the presence of the ore for re-use.

115

2. A process for the removing of the volatile compounds or metals in a volatilization extraction, which consists in the volatilization of the metals in ore in a closed chamber passing a carrier gas through said chamber, whereby the volatile compounds may be absorbed thereby, passing the carrier gas with the volatile compounds therein to a closed fume arrester, wherein a part or all of the volatile compounds are arrested, and passing the carrier gas with any uncaught volatile compounds from the fume arrester back 120

125

130

again to the volatilization chamber, whereby said carrier gas may be re-used as a conveyer for the volatile compounds.

3. A process for the removing of the volatile compounds or metals in a volatilization extraction, which consists in passing nitrogen gas and a halogen gas into a closed heated chamber containing the crushed ore to be volatilized, wherein said ore is chemically acted upon by the halogen gas and the volatile compounds formed absorbed by the nitrogen gas, passing the nitrogen gas with the volatile compounds therein to a closed fume arrester wherein a greater portion of

the volatile compounds are separated from 15 the nitrogen gas, passing the nitrogen gas with the remaining volatile compounds therein to a mixing chamber and applying said mixing chamber with additional halogen gas and passing the mixed gas from 20 the mixing chamber to said closed volatilization chamber.

In testimony whereof I affix my signature, in presence of two witnesses.

SELDEN IRWIN CLAWSON.
